UNITED STATES PATENT OFFICE.

IRVING R. BAILEY, OF AKRON, OHIO, ASSIGNOR TO THE GOODYEAR TIRE AND RUBBER COMPANY, OF AKRON, OHIO, A CORPORATION OF OHIO.

RUBBER HEEL.

1,141,227.

Specification of Letters Patent.

Patented June 1, 1915.

Application filed November 2, 1914. Serial No. 869,848.

To all whom it may concern:

Be it known that I, IRVING R. BAILEY, a citizen of the United States, residing at Akron, in the county of Summit and State of Ohio, have invented new and useful Improvements in Rubber Heels, of which the following is a specification.

This invention relates to improvements in rubber heels for boots and shoes, and the object thereof is to provide an improved heel of some elastic material such as rubber which can be readily attached to the ordinary heel of a boot or shoe, and possessing superior lasting qualities and means which effectually prevent slipping or skidding.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings, in which similar reference numerals indicate like parts in the different figures, Figure 1, is a perspective view of a heel looking at the under face thereof; and, Fig. 2, is a longitudinal, central, sectional view enlarged of the heel shown in Fig. 1.

The heel which forms the subject matter of this invention comprises a body 1 of an elastic material such as rubber, having an under face 2 and an upper face 3 and with the outer edge fashioned to approximately coincide with the leather heel of a boot or shoe to which it is to be attached. The heel is formed with a plurality of raised integral lugs on the lower face thereof, the arrangement of which is discretionary, and in these raised lugs and the adjacent body portions are upwardly-extending frusto-conically formed shallow recesses 4, the open ends of which are outwardly flared and preferably arranged concentrically with respect to the lugs and of such a size as to provide a marginal beading 5 surrounding the recesses and having inclined walls which slope upwardly and merge into the under face 2 of the heel 1. Communicating with the upper portions of the recesses 4 are recesses 6 hav-

ing lower inclined walls of greater inclination than are the walls of the recesses 4. Extending upwardly from the recesses 6 and in open communication therewith are cylindrical recesses 7 terminating near the transverse median portions of the heel. Embedded in the body of rubber by the vulcanization thereof at the upper termini of the recesses 7 are apertured disks or washers 8 the openings 9 therein being preferably in alignment with the axes of the recesses 7. The heel is secured in position by applying the upper face 3 to the under side of the leather heel and then suitably formed nails or other fastening means are passed through the cylindrical recesses 7 and apertures 9 and the pointed ends thereof are driven through the balance of the material which exists between the washers and the upper face 3 and into the leather heel by which the heel is secured.

In ordinary practice the nails should be so driven that the heads engage and bear against the washers 8 which serve as abutments for them and the washers serve to extend the anchorage of the heads in a larger volume of rubber than would be possible by use of the heads alone. The heads ordinarily will be driven entirely into the recesses 7 so as to leave the cup-shaped recesses 4 and 6 approximately unobstructed. By providing the lugs on the under face of the heel and from which the annular beadings 5 are formed by the recesses 4, the thickness of the heel is increased without appreciably increasing the weight thereof and the capacity of the recesses are enlarged to afford a greater suction or vacuum action when the heel is under compression and use.

Experience has shown, that when in use the weight of the wearer of the shoe will slightly compress or distort the beads 5 and thereby effectually form an approximately tight joint with the surface on which the shoe rests to slightly reduce the capacity of the recess so that when the heel is raised a vacuum cup action is set up, tending to hold the heel against slipping or skidding, especially on wet pavements. Furthermore, the provision of the lugs from which the annular beadings 5 are formed, greatly increases the life of the heel and adds to its wearing qualities and also enables it to give a more even engagement with side walks or pavements which are irregular or rough.

I claim:

A heel tread comprising a body of elastic material provided on its lower face with a plurality of downwardly-projecting integral lugs each in the general form of a conic frustum and each lug provided with an upwardly-extending and centrally-disposed frusto-conically-formed recess, the body above each recess provided with an upwardly-extending recess axially-disposed with reference to one of the first recesses and in open communication therewith, the upper end of each upper recess provided with a

relatively wide flat communicating enlargement, and an apertured washer positioned in each enlargement and with its axis in alignment with the axis in the upper recess, said washers providing anchorages for the heads of nails used for holding the heel in position. 15

In testimony whereof I have hereunto set 20 my hand in presence of two subscribing witnesses.

IRVING R. BAILEY.
